UNITED STATES PATENT OFFICE.

ALPHONSO V. WILBUR, OF STOCKTON, CALIFORNIA, ASSIGNOR TO HENRY C. SHAW, OF SAME PLACE.

GANG-PLOW.

SPECIFICATION forming part of Letters Patent No. 617,377, dated January 10, 1899.

Application filed February 18, 1898. Serial No. 670,851. (No model.)

To all whom it may concern:

Be it known that I, ALPHONSO V. WILBUR, a citizen of the United States, residing at Stockton, in the county of San Joaquin and State of California, have invented certain new and useful Improvements in Gang-Plows; and I do hereby declare the following to be a full, clear, and exact description of said invention, such as will enable others skilled in the art

10 to which it most nearly appertains to make, use, and practice the same.

This invention relates to improvements in plows, and more particularly to gang-plows; and it consists in the novel construction and 15 arrangement of the various parts whereby a land-gage is provided, together with a suitable and convenient mechanism for shifting the same, to alter the line of draft, and whereby the axle of the gage-wheel is utilized as a draw- 20 bar in connection with the said gage.

In the drawings, Figure 1 is a plan view of the attachments shown in connection with a plow of the style mentioned, the frame whereof is shown in dotted lines. Fig. 2 is a side elevation in detail of the lever for shifting the 25 line of draft, showing the manner of suspending the same on the frame of the plow. Fig. 3 is a detail view, partly in section, of the 30 detent-latch for locking the lever in position. Fig. 4 is a detail view, in front elevation, of a section of the draw-bar with a set-sleeve for controlling the line of draft.

Heretofore various devices have been used for shifting the line of draft upon the bar 35 extended across the front of the plow-frame and known as a "draw-bar." The best of these have consisted of double sprocket-wheels mounted in vertical shafts at either end of the draw-bar, upon which has been mounted a 40 chain, the free ends of which are attached to and control the position of the draft-link of the plow. By winding and unwinding the chain upon the sprocket this link has been shifted from side to side, thereby changing 45 the line of draft. This has been known as a "land-gage," and it is to accomplish the same purpose in a simpler and more convenient manner that I have provided the attachments shown in the drawings.

50 In the plows of the kind known as "gang-plows" they have usually been provided with

a gage-wheel at the forward end, on the right-hand side of the plow, to run in the bottom of the last furrow previously made. It is by means of this wheel that the various depths 55 are set at which it is desired to plow. When the gage-wheel extends to the same level as the plow-bottoms, the furrows will sink to the same depth as the former furrows, (or until the gage-wheel strikes on the bottom of the former 60 furrow.)

In the present invention the axle of the gage-wheel A is set back to form the lifting-arm A' and is extended across the front of the frame of the plow to form the portion A², 65 which is herein utilized as the draft-bar. The portion A² of the axle is mounted in bearings A³ A⁴, which are extended down from the forward end of the beams of the plow by means of bolts A⁴ A⁴. Loosely mounted to 70 slide upon this portion A² of the axle is a sleeve B, which is provided in the upper portion with a pin B', having an elongated head B². The sleeve B is also provided on the under part with an eye B³, formed integrally with the sleeve. The pin B' is extended to receive and hold the forward end of the lever C, the loop C' being formed on the end thereof to fit over the barrel of the pin and under the head. The eye B³ is intended to hold loosely the draft-rod D as it extends forward from its holding-strap D', 75 which is secured to the plow-beam X. The strap D' is bolted to the plow-beam by means of the bolts D² D². At the forward end the 80 draft-rod D is provided with the eye D³ to receive the draft-link D⁴. It is to the draft-link D⁴ that the team is hitched. It now will be seen that as the team is hitched to the draft-link D⁴ at the forward end of the draft-rod D the line of draft for the implement will be changed to the right or left as the sleeve B is thrown to the left or right, or, in other words, that the draft will be increased 85 to the side of the implement to which the end of the draft-rod D is shifted.

The end of the draft-rod D may be shifted by means of the lever C and its attachments, (shown in the drawings at Fig. 1,) or it may be shifted by hand and held by means of the 100 set-screw B⁴, by tightening which the sleeve B may be set rigidly upon any point on the

draft-bar or the portion A² of the axle, which here serves the purpose of the draft-bar. This method, however, is inconvenient, as it necessitates the stopping of the team and the backing of the same to slack the draft-chains in order that the sleeve may be shifted. It may, however, be used in that manner. When, however, it is desired to have the implement as easy to manipulate as possible, 10 the lever C is used to shift the end of the draft-rod by shifting the sleeve B and by locking the lever C in position to lock the draft-rod in position. The lever and its attachments, as shown in Fig. 1, consist of the lever C, fulcrumed to a detent-frame C², which is pivotally mounted upon the bolt C³, extending through the lower end of the bifurcated frame C⁴, which is secured to the cross-beam X' of the plow-frame by suitable bolts. 15 20 The lever is fulcrumed in the forward end of the detent-frame C² on a bolt C⁵ and within a slot formed by a bridge C⁶, extending up from the frame C². As before stated, in the forward end the lever is provided with an elongated slot C', which fits around the pin B' and by the elongation of which accommodates the variation of the arc of its movement to the straight line of travel of the sleeve B and the pin B'. The lever is set and 25 30 locked in position by means of the latch C⁷, which is provided at the lower end with two detent-teeth C⁸, adapted to strike in and hold on the teeth of the detent C². The latch C⁷ is thrown against the detent by the spiral spring C⁹, which expands against the lower 35 40 wall of a hollow formed in the casting, and a cotter-pin C¹⁰. The latch fits around the lever C, being provided with guide-slots cast in it. To the upper end of the latch is connected the connecting-rod C¹¹, which connects the latch to the rocking pull-lever C¹². By depressing the rocking lever C¹² the connecting-rod C¹¹ and latch are drawn toward the handle of the lever C, raising the latch C⁷ 45 and freeing the lever to move about the fulcrum or bolt C⁵. As stated, to move the lever C causes the sleeve B and draft-rod D to move, and thus change the line of draft of the implement. 50 55 By the term "line of draft," heretofore used, has been meant the pulling strain with reference to the lateral or side pull to guide the plow or correct any tendency which it might have in certain soils to drift sidewise. By the "collar-draft" is meant the height at which the draft-bar is placed to increase or diminish the lifting tendency which the pull of the team has on the forward end of the plow. By changing the collar-draft the an-

gle of the plow-bottom is changed. It is to 60 change the collar-draft that the draft-bar is here mounted in the bearings at the end of the bolts A⁴ A⁴, which are raised and lowered on the plow-beams, and thereby change the collar-draft. To brace these bearings A³ A³, 65 the flat braces A⁵, A⁵, and A⁶ are used, the former extending in line with the beams and the latter extending across these, as shown at Fig. 1 of drawings. It is because of the change of the height of the draft-bar also that 70 the detent-frame C² is pivotally mounted on the frame C⁴. By this mounting the draft-bar may be lowered or raised and the lever C will swing with it.

To operate the gage-wheel to raise and 75 lower the same, there is provided a device for rotating the portion A² of the axle. Any suitable device may be used; but the particular device used by me is shown and described in a companion application to this. 80

Having thus described this invention, it is claimed—

1. In a plow the combination of a draft-bar extended across the front of a plow-frame; suitable hangings by which the said bar may 85 be raised and lowered; a loose sleeve to slide on the said bar and adapted to support the draft-link; a lever loosely engaging the said sleeve, and fulcrumed in a swinging frame; and a swinging frame provided with the fulcrum for the lever and a locking device to set the lever in position and pivotally mounted on the frame of a plow, substantially as described.

2. In a plow the combination of a draft-bar 95 extended across the front of a plow-frame; suitable hangings by which the said bar may be raised and lowered; a draft-rod pivotally connected to the plow-frame at the rear; a loose sleeve to slide on the said bar and adapted to support the forward end of the draft-rod; a lever loosely engaging the said sleeve and fulcrumed in a swinging frame to shift the sleeve from side to side; a swinging frame provided with a detent-rack and a fulcrum 100 for the said lever and pivotally mounted in a frame extended down from the frame of the plow; and a latch mounted to slide on the lever to engage the detent-rack and provided with a spring and lever to move it in opposite 105 directions to lock and unlock the lever, substantially as described.

In testimony whereof I have hereunto set my hand this 12th day of January, 1898.
